CLAIM

The ornamental design for a storage container, as shown and described.

DESCRIPTION

FIG. 1 is a top perspective view of a storage container showing our new design.

FIG. 2 is bottom perspective view thereof.

FIG. 3 is a top view thereof.

FIG. 4 is a bottom view thereof.

FIG. 5 is a right side view thereof.

FIG. 6 is a left side view thereof.

FIG. 7 is a front view thereof; and,

FIG. 8 is a back view thereof.

The broken lines represent portions of the storage container that form no part of the claimed design.
